DESIGN FOR A RAZOR

Don A. Birrell, Salt Lake City, Utah

Application August 15, 1940, Serial No. 94,432

Term of patent 3½ years

To all whom it may concern:

Be it known that I, Don A. Birrell, a citizen of the United States, residing at Salt Lake City, in the county of Salt Lake and State of Utah, have invented a new, original, and ornamental Design for Razors, of which the following is a specification, reference being had to the accompanying drawing, forming a part thereof.

I claim:

The ornamental design for a razor, as shown.

DON A. BIRRELL.
